TO THE SIMPLEX RADIO COMPANY, OF SANDUSKY, OHIO, A CORPORATION OF OHIO

UNITARY CONTROL FOR CONDENSERS

Application filed December 9, 1926, Serial No. 153,528. Renewed June 11, 1932.

This invention relates to radio apparatus and more particularly to a unitary control means, or what is more commonly known as single dial control, for controlling the capacities of a plurality of variable condensers ordinarily introduced in the radio frequency circuits of a radio receiving apparatus.

Attempts have been made, at various times, to provide a means whereby a plurality of variable condensers could be controlled or operated simultaneously from a single controlling member or dial, but they have been more or less inefficient because of the fact that the variable condenser of the first stage radio frequency amplification, or the variable condenser introduced into the antenna circuit, could not be adjusted at the same rate of change of capacity as the variable condensers of the remaining or following stages of radio frequency amplifying circuits. This was due to the fact that the normal capacity of the variable condenser of the antenna circuit was increased by the capacity of the antenna itself, so that the total capacity of the variable condenser of the first stage of radio frequency amplification was exceedingly greater than the capacities of the variable condensers of the following stages of radio frequency amplification. Therefore, from the foregoing it will be seen that an accurate "tuning in" could not be effected where the capacities of the variable condensers were normally the same and where these variable condensers were adjusted simultaneously at the same rate of change in capacity. By means of this invention this objection has been overcome and it is possible to tune each circuit in resonance with each of the other circuits by the operation of a single selector member or dial.

It is a further object of the invention to provide a separate means for varying the capacity of the variable condenser of the first stage of radio frequency amplification so that a more accurate "tuning in" may be afforded, the result being much clearer and a much more accurate reception.

In order to compensate for the added capacity of the antenna to the capacity of the variable condenser of the first stage of radio frequency amplification, means is provided

whereby a more rapid variation in the capacity of the variable condenser of the first stage of radio frequency amplification is permitted than the change in capacity of the variable condensers of the remaining stages, thereby providing for accurate adjustment of the plurality of condensers to different wave lengths simultaneously. 55

With the objects above indicated and other objects hereinafter explained in view, our invention consists in the construction and combination of elements hereinafter described and claimed. 60

Referring to the drawings:

Fig. 1 is a front elevational view of the 65 disks with the panel removed except as to that portion including the graduations.

Fig. 2 is a top plan view of the apparatus.

Fig. 3 is a bottom plan view showing the 70 location of the vernier condenser.

Fig. 4 is an enlarged front elevational view 75 of the disk secured to the first condenser.

Fig. 5 is a bottom plan view of the disk shown in Fig. 4.

Fig. 6 is an enlarged front elevational view 75 of the disk secured to the second condenser.

Fig. 7 is a top plan view of the disk shown in Fig. 6. 80

Fig. 8 is an enlarged front elevational view 80 of the disk secured to the third condenser.

Fig. 9 is a top plan view of the disk shown in Fig. 8. 85

In the drawings, 10 represents the sub-base which is composed of suitable insulating material and adapted to support the various apparatus to which is secured, at the front edge, a vertically extending insulated panel 11, while 12, shown in dotted lines, represents the panel positioned in front of the radio receiving apparatus. This panel 11 has etched 90 thereon calibrations 13 which indicate the various wave lengths. Secured to the panel 11 by means of bolts or other suitable means, are condensers 14, 15 and 16 properly spaced apart. These condensers are provided with 95 the customary rotor and stator plates, the rotor plates being mounted for rotation upon the shafts 17, 18 and 19, respectively, these shafts extending a substantial distance beyond the outer face of the panel 11. This 100

shaft 18 of the center condenser 15 extends further outwardly than the shafts 17 and 19 and through a suitable opening in the panel 12 and has secured to its outer end a pointer 20 which co-operates with the calibrations 13 on the panel 12.

The condensers 14, 15 and 16 are provided with the usual rotor terminals 21 and stator terminals 22 to which may be secured the proper conductors.

A disk 23 is provided along its outer periphery with a groove 24 and a hub 25 having a central opening 26 therethrough. This hub 25 is pinned to the outer end of the shaft 17 so that rotation of the disk 23 causes the rotor plates of the condenser 14 to rotate in the same direction. A disk 26, similar to the disk 23, is provided around its periphery, with a groove 27 and a hub 28 having a central opening 28a. This hub 28 is pinned to the shaft 19 so that the rotor plates carried by the shaft 19 will rotate simultaneously with the rotation of the disk 26.

A disk 29 of a greater thickness than the disk 23 or 26, is provided with peripheral parallel grooves 30, 31 and 32 and an axially extending hub 33 which has a central opening 34 extending entirely through the hub 33 and disk 29. This disk is interposed between the pointer 20 and the condenser 15 and is secured to the shaft 18 by a pin extending through the hub 33 and the shaft 18 so that this disk 29 likewise rotates simultaneously with the rotor plates of the condenser 15. The rotation of this disk 29, however, is limited by the engagement of stops 35 and 36 with the upper edge of the panel 11, care being taken to locate or position these stops so that when one or the other of the stops engage the upper edge of the panel 11 the rotor plates of the condenser 15 are either entirely interleaving with the stator plates or entirely out of engagement therewith.

As has been heretofore explained in the objects, it is necessary to provide for regulating the capacity of condenser 14 so that there is a more rapid change in capacity taking place therein, than with the condensers 15 and 16, due to the fact that the capacity of the condenser 14 is substantially increased by the introduction of the antenna into the circuit of which this condenser 14 is a part. This increase in the change of capacity in condenser 14 has, therefore, been provided by reducing the external diameter of the disk 23 with respect to the external diameters of the disks 29 and 26, the condensers here shown being of certain maximum capacities. It has been found that the proper increase of variation of capacity may be obtained in condenser 14 by providing the disk 23 with an external diameter of approximately $2\frac{13}{16}$ " while the diameters of disks 26 and 29 should be substantially 8" in diameter. It is to be understood, however, that the relative diam-

eters of these disks may be changed so long as the required rate of change in capacity of the condenser 14 is proportional to the rate of change in capacity of condensers 15 and 16, this rate of change being determined by the capacity added to condenser 14 by the antenna.

As a means for rotating the disks simultaneously a cable arrangement has been employed, the primary feature of which is to maintain a degree of tension upon the various cables between the adjacent disks so as to prevent any likelihood of slippage or variation between the rotation of the disks. With the rotor plates of the condensers entirely out of engagement with the stator plates of the condensers as shown in Fig. 2, the disks 23, 26 and 29 assume the relative positions shown in Figs. 4, 6, and 8. The disk 23 is provided with an angularly extending slot 37 which extends entirely through the disk, a spring 38 being disposed within the slot 37 and which has one end secured to the disk at 39 while the opposite end is secured to a cable 40, preferably of fine piano wire or the like, which cable extends through an opening 41 in the disk 23 and is received by the groove 24. This cable 40 extends into engagement with the groove 30 of the disk 29 and the end passes through an opening 42 and is looped over a pin at 43, then passes outward through opening 42, continuing around 29 in the same groove 30, extends into engagement with groove 24 of disk 23, continuing in the same direction around 23 to an opening 41 through which it passes to be secured at 45. It will be seen that this cable 40 is always under tension due to the action of the spring 38 thereon.

The disk 26 is provided with an elongated slot 47 extending on the opposite side of the center from the slot 37 in the disk 23 but in a parallel direction thereto. This slot 47 has disposed therein a spring 48 which has one end secured as indicated at 49 to the disk 26 while the opposite end is attached to a cable 50 which extends through an opening 51 into and is seated within the groove 27 and extends into the groove 31 of the drum 29 in a counterclockwise direction and passes through an opening in the disk 29 where it loops over a pin at 51 and outward through the same opening, following groove 31 of disk 29, until it has encircled 180° of 29, then extending on to disk 26 where it engages groove 27, following around in counterclockwise direction to an opening 51 through which it passes and is securely fastened to disk 26 at 53.

It will be seen from the foregoing description that any rotation or movement of the shaft 18 of the condenser 15 will cause a similar movement of the shafts 17 and 19 through the medium of the cables and that these cables are prevented from slipping within the

grooves of the respective disks by means of the tension imposed therein by the springs of the disks 23 and 26.

Directly below the shaft 18 of the condenser 15 is a tubular sleeve 54 which extends through an opening in the panel 12 and has its inner end journaled within the panel 11. This sleeve 54 carries midway between the panel 11 and 12 a grooved pulley wheel 55 securely attached thereto. This pulley wheel 55 is positioned so that the groove 56 is directly beneath the groove 32 of the disk 29. This pulley wheel 55 receives within the groove 56 the cable 57 which extends counterclockwise around the disk 29 within the groove 32 having one end attached to a spring 58 disposed within a slot 59 formed at the lower portion of the disk 29 while the opposite end of the spring 58 is secured to the disk 29 as indicated at 60. The opposite end of this cable 57 extends through an opening provided in the groove of the disk 29 and is secured to the disk as indicated at 61. This sleeve 54 has secured thereto, to the portion extending beyond the panel 12, a knob 63 rotation of which causes rotation of the sleeve 54 carrying the pulley wheel 55. It will be seen, therefore, through the arrangement of cables heretofore described that any rotary movement of the knob 63 will be imparted to the disk 29 which in turn will impart this rotary motion to the disks 23 and 26. The disks 29 and 26 will rotate at the same rate of speed, due to the fact that the diameters of these disks are the same, but the rotation of the disk 23 will be more rapid in either direction due to the reduced diameter of the disk 23 with respect to the diameters of the disks 29 and 26, the capacity of the condenser 14 therefore being changed more rapidly than the capacities of the remaining condensers.

To obtain a more delicate and accurate adjustment the rotor of the first condenser 14 has one less plate than the rotors of the remaining condensers. To compensate for this reduction in capacity of the condenser 14 a vernier or trimming condenser 64, of a capacity sufficient to bring the capacity of the condenser 14 equal to either of the capacities of the condensers 15 or 16, is connected in parallel to the condenser 14. This condenser 64 is provided with a rotor shaft 65 which extends centrally through the sleeve 54 and knob 63 and has secured to the extending end a knob 66 for permitting adjustment of the rotor plates with respect to the stator. This vernier condenser is mounted on the panel 11 through the bracket 67 which is riveted or otherwise securely fastened to the panel 11. This vernier condenser is provided with the usual stator terminal 68 and rotor terminal 69 which are connected by means of conductors to the stator terminal 22 of the condenser 14 and the rotor terminal 21 respectively. It will, there-

fore, be seen from this arrangement that the capacity of the condenser 14 can be more minutely regulated than if an additional rotor plate were included with the rotor plates of the condenser 14.

In the operation of the device it is only necessary to rotate the knob 63 in either direction, depending upon the desired wave length or station to be received, this rotation simultaneously and proportionately changing the capacities of the condensers for resonantly "tuning in" the incoming waves. When the desired station has been located and "tuned in" additional quality or clearness may be obtained by the rotation of the knob 66 thereby adjusting the capacity of the vernier condenser which, being parallel with condenser 14, more finely adjusts the capacity of that condenser.

Having thus described our invention, what we claim is:

1. In a radio receiving apparatus, a plurality of variable condensers, rotary control members for each of said condensers disposed in the same horizontal plane and means interconnecting said rotary control members for varying the capacities of said condensers simultaneously, the capacity of one of said condensers being more rapidly varied than the others, said means being resiliently attached to each of said rotary control members for synchronously moving said condensers.

2. In a radio receiving apparatus, a plurality of variable condensers, drive shafts for each of said condensers disposed in the same plane, a disk secured to the drive shaft of each of said condensers, cables resiliently interconnecting each of said disks, said cables being rigidly attached to one disk and flexibly attached to the adjacent disk and a unitary operating member for imparting movement to said disks.

3. In a radio receiving apparatus, a plurality of condensers, each provided with a rotatable shaft, said shafts being disposed in the same plane, a disk secured to each of said shafts, cables fastened between the adjacent disks, means interposed in said cables for subjecting said cables to tension intermediate said disks and a single control means connected to one of said disks for causing angular adjustment of said disks.

4. In a radio receiving apparatus, a plurality of condensers, rotatable shafts on each condenser, said shafts being disposed in the same horizontal plane, disks on said shafts, one of said disks being of reduced diameter, yieldable means disposed within the confines of certain of said disks, means extending from said yieldable means for connecting said disks together to cause simultaneous angular movement thereof, and a unitary actuating member for imparting simultaneous adjustment to said disks.

5. In a radio receiving apparatus, a plu-

rality of condensers, rotatable shafts on each condenser, said shafts being disposed in the same horizontal plane, disks on said shafts, one of said disks being of reduced diameter, means connecting said disks together to cause simultaneous angular movement thereof, a unitary actuating member connected to one of said disks for imparting angular adjustment to said shafts and tension means supported by certain of said disks, said tension means being disposed in series with said connecting means.

6. In a radio receiving apparatus, a plurality of variable condensers provided with 15 rotatable shafts, grooved disks secured to said shafts, tension cables engaging the grooves of said disks and permanently secured adjacent the peripheries of said disks and adapted to cause simultaneous rotation of 20 said disks, a unitary operating member, and means between said member and one of said disks whereby the rotation of said operating member causes a like rotation of said disks.

7. In a radio receiving apparatus, a plurality of variable condensers, each provided 25 with a rotatable shaft, said shafts being disposed in the same horizontal plane, a disk secured to each shaft, one of said disks being of less diameter than adjacent disks, a cable 30 connecting the disk of less diameter with the adjacent disk and a cable connecting the adjacent disk with a disk on the opposite side from the disk of less diameter, a single operating member, a cable connected to said operating member and one of said disks so 35 that rotation of said operating member causes a similar rotation of said disks and coil springs extending chordal to certain of said disks, each of said coil springs being anchored at one end to its associated disk and connected at the other end to said cable.

8. As an article of manufacture a set of 45 disks each provided with an opening adapted to be secured to the rotary shafts of a plurality of variable condensers, one of said disks being of less diameter than adjacent disks, means for connecting said disks together the axes of said disks being aligned in the same horizontal plane for simultaneous angular 50 movement, an operating member, means for connecting said operating member to one of said disks certain of said disks having a recess extending substantially chordal thereof and a spring disposed in the recess and 55 anchored at one end to said disk and at the other end to said connecting means.

9. In a radio receiving apparatus, a plurality of variable condensers each having a 60 rotary member adjustable for varying the capacities of said condensers, said rotary members all being disposed in the same horizontal plane, a single operating member 65 symmetrically arranged with respect to all of said rotary members for simultaneously varying the capacity of said condensers, and

means for effecting a more rapid variation in capacity of one of said condensers comprising a cable interconnecting said single operating member with one of said rotary members and individual cables interconnecting said last mentioned rotary member with each of the other rotary members and secured therebetween, and means for independently tensioning each of said cables for effecting synchronous movement of said rotary members, said means comprising a coil spring supported within the limits of certain of said rotary members, each of said coil springs being anchored at one end to its associated rotary member and connected at its other end to said cables.

10. Tuning apparatus comprising a multiplicity of condensers spaced one from another and having actuating shafts extending substantially parallel one to another, a driving disk on each of said actuating shafts, said driving disks each being grooved at the peripheries thereof, flexible drive means positively connected to said disks and moving in the grooved peripheries thereof, tension means included in each of said flexible drive means, and a separately tensioned cord positively connected to one of said driving disks for shifting all of said driving disks simultaneously for the unitary control of the several condensers connected thereto.

11. Tuning apparatus comprising a multiplicity of variable condensers each having rotary actuating shafts extending substantially parallel one to another, driving disks 100 carried by each of said shafts, flexible drive cords positively interconnecting said driving disks, a resilient device carried by each of said driving disks for subjecting said driving cords to tension, and a flexible driving cord connected to one of said driving disks for imparting motion thereto and simultaneously moving said driving disks for the unitary control of all of said variable condensers.

12. Tuning apparatus comprising a multiplicity of variable impedance devices, rotary actuating shafts connected with said variable impedance devices and extending substantially parallel one to another, driving disks carried by each of said rotary actuating shafts, grooves in the peripheries of each of said driving disks, flexible cords extending around the grooves of said disks and interconnecting selected disks, a spring carried by each of said driving disks, each spring having one end thereof anchored to the driving disk and the other end thereof connected to one of the flexible cords for the positive interconnection of said disks, and a flexible cord drive connected with one of said driving disks for imparting rotary motion thereto and simultaneously driving all of said rotary actuating shafts in synchronism.

13. In a control system for radio broadcast receivers, a multiplicity of independent variable tuning devices, rotatable shafts for each of said devices, a pulley member on each of said shafts, means interconnecting the said pulley members and extending around the peripheral edges thereof, said means being rigidly attached to one of said pulley members and flexibly attached to the other of said pulley members, and means for imparting movement to all of said pulley members.

10 In testimony whereof, we hereunto affix our signatures.
